CHARLES M. THEBERATH, OF NEWARK, NEW JERSEY.

Design No. 5,006, dated June 13, 1871.

DESIGN FOR HARNESS-TRIMMING.

The Schedule referred to in these Letters Patent and making part of the same.

To all whom it may concern:

Be it known that I, CHARLES M. THEBERATH, of Newark, in the county of Essex and State of New Jersey, have invented a new and original Design for Harness-Trimming; and I do hereby declare that the following is a full, clear, and exact description thereof, which will enable others skilled in the art to make and use the same, reference being had to the accompanying drawing forming part of this specification.

Figures 1 and 2 are side views of my new design for harness-trimmings.

Figures 3 and 4 are end views of the same.

Similar letters of reference indicate corresponding parts.

This invention relates to a new design for harness-trimming, or rather for the covering thereof, and consists in the formation of a groove or imitation seam near each edge of each covering.

A and B in the drawing are two harness-trimmings of suitable form and purpose. They are usually covered with leather, rubber, or equivalent material.

The surfaces thus covered are provided with grooves

or imitation seams *a a*, one near each edge, so that the portion *b*, between such seams or grooves, will be arched or raised, as is clearly shown in figs. 3 and 4.

The outer parts, *c c*, project somewhat above the groove, so that thus the covered edge of each harness-trimming will form a cross-section similar to the letter **W**.

The effect thus produced by the covering of the trimming is quite original and novel, while the new form is also useful.

Hitherto the covering usually formed a projecting ridge in the middle for the reception of the cross-seam, producing thus an unsightly affair, and a cover altogether too much exposed to dust and wear to be preserved from rapid wear and kept clean.

I claim as my invention—

The covering for harness-trimming, arched or raised in the middle and grooved near the side, as set forth.

CHARLES M. THEBERATH.
